ATTORNEY

UNITED STATES PATENT OFFICE

114,058

DESIGN FOR A VANITY CASE OR SIMILAR ARTICLE

Lloyd J. Davenport, Kearny, N. J., assignor to
Paul E. Flato, New York, N. Y.

Application June 17, 1938, Serial No. 77,903

Term of patent 3½ years

To all whom it may concern:

Be it known that Lloyd J. Davenport, citizen of the United States and resident of Kearny, in the county of Hudson and State of New Jersey, has invented a new, original, and ornamental Design for a Vanity Case or Similar Article, of which the following is a specification, reference being had to the accompanying drawing, forming part thereof, in which,

Fig. 1 is a top plan view of a vanity case or similar article embodying my new design;

Fig. 2 is a rear end view thereof;

Fig. 3 is a vertical side elevational view thereof.

Fig. 4 is a view of the other side;

Fig. 5 is a front end view; and

Fig. 6 is a bottom plan view thereof.

The dominant feature of the present design resides in a rectangular metal vanity case or sim-

ilar article having on its upper and lower faces a pair of metallic ridges integral with the body of the case, each of said ridges extending across the entire face and being ornamented to resemble twisting, one of the ridges on each face being disposed parallel to one pair of parallel edges and nearer one of said pair and the other ridge being disposed rectangularly to the first ridge and parallel to the other pair of parallel edges and nearer one of said pair, each face being thereby divided into four rectangular unequal areas one at each corner and separated from each other by said ridges.

I claim:

The ornamental design for a vanity case or similar article, substantially as shown and described.

LLOYD J. DAVENPORT.
